ELMER W. DAVIS, OF NEWTON, MASSACHUSETTS, ASSIGNOR, BY MESNE ASSIGNMENTS, TO REMINGTON RAND INC., OF BUFFALO, NEW YORK, A CORPORATION OF DELAWARE

FOLLOW BLOCK

Application filed July 9, 1929. Serial No. 376,997.

This invention relates to a follow block and more particularly to a compression spring follow block.

This invention has for an object to provide a follow block of the compression spring type which is simple in construction and adapted to cooperate with a simple form of filing tray.

Another object of this invention is to provide a follow block having means which automatically locks against movement at any point in the length of a filing tray and yet may be instantly released and moved backwards or forwards as desired.

A further object of this invention is to provide a filing tray having guides such as channels in each side thereof cooperating with means carried by the follow block, whereby said block may be locked in any desired position.

A specific object of this invention is to provide a filing tray having channels in the longitudinal walls thereof cooperating with spring-controlled means mounted on a follow block, whereby said block may be locked in any desired position in the tray or moved as desired.

Other objects will appear from the following description, appended claims and accompanying drawing forming a part of this specification and in which:

Figure 1 illustrates a rear view of a follow block locked in position in a tray, the tray being shown in section.

Figure 2 is a section taken on lines I—I of Figure 1.

Figure 3 is a top plan view of the spring and cross-bars removed from the block.

Referring to the drawing wherein like reference numerals designate like parts, the reference numeral 1 designates a follow block made of any suitable material such as aluminum. The upper edge 2 is rounded by being bent backward and the side edges 3 and 4 are bent rearward at substantially right angles to the face of the block. The block is so disposed in the filing tray 5 that it is inclined or slopes away from the cards or other records disposed therein, whereby sufficient space at the top

of the cards is provided for flexing or moving the cards or records. The sides or ends 3 and 4 of the follow block are provided with slots 6 and 7 respectively. Extending through these slots and slidably disposed therein is a spring 8 having a bowed portion 9 in the central portion thereof for reasons which will become apparent. It is preferred that the fit of the spring 8 in the slots 6 and 7 be as close as practical to retain the sliding connection between the members so that the block is maintained against any substantial rotational movement by the spring. On each end of the spring 8 there is secured by welding or the like a cross-bar 10 which is adapted to cooperate with channels 11 formed in the sides of the tray and extending longitudinally thereof. Due to the structure and resiliency of the spring in its normal position it exerts a pressure whereby the cross-bars 10 engage the channels 11, thus preventing movement and locking the follow block. The channels 11 not only cooperate with the cross-bars 10 to form a locking means but may also serve as a guide when the block is moved.

To prevent the rocking of the spring assembly in the tray, the cross-bars 10 are made longer than the width of the spring 8. The spring may also be centralized on the block, especially when the latter is removed from the tray, by means of pins 12. These pins are driven through the spring close to the bent-back edges of the block and limit the side motion of the block relative to the tray.

Inasmuch as the spring 8 is utilized as a mounting member for the follow block, the rigidity with which the block stands in the tray depends largely upon the shape of the edges of the cross-bars 10 coming in contact with the channels 11. Thus, rounded edges are to be avoided. If desired, in order to obtain a more positive locking action, the cross-bars 10 and the channels 11 may be knurled, roughened or otherwise treated as indicated at 13 and 14 respectively to insure a more positive contact.

In use to adjust the follow block forward or backward to compensate for the varying

number of cards in a file, it is only necessary to release the pressure on the cross-bars 10 against the walls of the channels 11. This is accomplished by placing one's fingers under the spring at the bowed portion thereof and the thumb at the top of the block on the rounded edge and pinching together, thus shortening the distance between the cross-bars 10. Slight contraction of the spring 8 makes it possible to shift the block in the tray by movement thereof. A greater contraction of the spring obtained by the use of sufficient pressure permits the block to be withdrawn from the tray.

15 Since it is obvious that various modifications may be made in the specific details above set forth, this invention is not restricted thereto except as defined in the appended claims.

20 I claim:

1. In combination, a filing tray having a channel extending longitudinally in each of the side walls thereof, a follow block, yielding means on said block having means cooperating with said channels whereby the block may be locked in any position, said yielding means and channel cooperating means forming the sole support for said follow block in said tray.

2. In combination, a filing tray having a channel extending longitudinally in each of the side walls thereof, a follow block, a contractable spring slidably secured to said block, a cross-bar mounted on each end of said spring, said cross-bars being normally maintained in contact with said channels by the spring whereby said block is locked against movement longitudinally of the tray and adapted to be moved out of contact upon the contraction of said spring whereby said block may be positioned at any position or withdrawn, said cross bars and spring normally supporting said block against substantial movement, said spring and said cross bars forming the sole support for said follow block.

3. In combination, a filing tray having a channel extending longitudinally in each of the side walls thereof, a follow block, a contractable spring slidably secured to said block, a cross-bar mounted on each end of said spring, said cross-bars being normally maintained in contact with said channels by the spring whereby said block is locked against movement longitudinally of the tray and adapted to be moved out of contact upon the contraction of said spring whereby said block may be positioned at any position or withdrawn, said cross-bars and spring wholly supporting and guiding said block, the contact surfaces of said cross-bars and channels having friction means to effect a more positive locking.

4. In combination, a filing tray having a channel extending longitudinally in each of

the side walls thereof, a follow block, a bowed contractable spring secured to said block, a cross-bar mounted on each end of said spring, said cross-bars being normally maintained in contact with said channels by said spring whereby said block is locked against movement longitudinally of the tray and adapted to be moved out of contact upon the contraction of said spring whereby said block may be positioned at any position or withdrawn, said cross-bars and spring wholly supporting said block.

5. In combination, a filing tray having a channel extending longitudinally in each of the side walls thereof, a follower block provided with end portions containing slots, a flat spring slidably mounted in the slots of said follower block, a cross-bar mounted on each end of said spring and releasably retained in its corresponding channel by said spring, said spring and cross-bars co-operating to hold said block in adjusted position and against substantial turning movement.

In testimony whereof, I have affixed my signature to this specification.

ELMER W. DAVIS.
